(57) **CLAIM**

The ornamental design for a wine bottle holder, as shown and described.

DESCRIPTION

FIG. 1 is a perspective view of a 7-bottle wine bottle holder showing our new design;

FIG. 2 is a front elevational view thereof;

FIG. 3 is a side elevational view thereof;

FIG. 4 is a top plan view thereof;

FIG. 5 is a bottom plan view thereof;

FIG. 6 is a perspective view of a second embodiment of a 4-bottle wine bottle holder;

FIG. 7 is a front elevational view thereof;

FIG. 8 is a side elevational view thereof;

FIG. 9 is a top plan view thereof;

FIG. 10 is a bottom plan view thereof;

FIG. 11 is a perspective view of a third embodiment of a wine bottle holder; and,

FIG. 12 is a front elevational view thereof.

The dotted lines in FIGS. 11 and 12 form no part of the claimed design and the subject matter shown in dotted lines discloses indeterminate length and that the wine bottle holder may be shorter or longer, with more or less uniformly spaced identically shaped holders.
